Primary Examiner — Katherine A Holbrow*Assistant Examiner* — Riya Salil Kamat(74) *Attorney, Agent, or Firm* — Amundsen Davis, LLC(57) **CLAIM**

The ornamental design for a gameboard, as shown and described.

DESCRIPTION

FIG. 1 is a perspective view of a gameboard showing a first embodiment of the claimed design;

FIG. 2 is a front view of that seen in FIG. 1;

FIG. 3 is an alternate perspective view of that seen in FIG. 1;

FIG. 4 is a perspective view of a gameboard, showing a second embodiment of the claimed design;

FIG. 5 is a front view of that seen in FIG. 4; and,

FIG. 6 is an alternate perspective view of that seen in FIG. 4.

In the drawings the broken lines depict portions of the gameboard that form no part of the claimed design.

1 Claim, 6 Drawing Sheets(56)
